FIG. 5.

Fig. 1 is a view in side elevation of a two-wheel tractor embodying our new design;

Fig. 2 is a similar view of the opposite side of the same tractor;

Fig. 3 is a front elevation of the same tractor;

Fig. 4 is a rear elevation of the same tractor; and

Fig. 5 is a plan view of the same tractor.

This application is a continuation-in-part of our earlier application Serial No. D. 55,253, filed March 30, 1959, now abandoned.

The essential features of our design reside in those portions shown in full lines.

We claim:

The ornamental design for a two-wheel tractor, substantially as shown and described.
